[57] CLAIM

The ornamental design for a carrying handle for bottles, as shown and described.

DESCRIPTION

FIG. 1 is a left side isometric view of the carrying handle for bottles showing my new design;

FIG. 2 is a right side elevational view thereof;

FIG. 3 is a rear elevational view thereof;

FIG. 4 is a top plan view thereof;

FIG. 5 is a front elevational view thereof; and,

FIG. 6 is a bottom plan view thereof.
